US0D1106673S

(12) **United States Design Patent** (10) Patent No.: **US D1,106,673 S**
(45) Date of Patent: ** Dec. 23, 2025

(54) **CASE FOR AN AUDIO EQUIPMENT CONTROLLER**

(71) Applicant: **Genelec Oy**, Iisalmi (FI)

(72) Inventors: **Jaakko Nisula**, Iisalmi (FI); **Harri Koskinen**, Iisalmi (FI); **Janne Räty**, Iisalmi (FI)

(73) Assignee: **GENELEC OY OLVITIE 5**, Iisalmi (FI)

(**) Term: **15 Years**

(21) Appl. No.: **29/949,576**

(22) Filed: **Jun. 27, 2024**

(30) **Foreign Application Priority Data**

Dec. 27, 2023 (EM) 015045803-0002
